(74) Attorney, Agent, or Firm — Buchalter, a professional corp.

(57) **CLAIM**

The ornamental design for a sleeve, as shown and described.

DESCRIPTION

FIG. 1 is a Bottom, Left perspective view of a sleeve on a user's arm showing my new design;

FIG. 2 is a Bottom, Right perspective view of the sleeve illustrated in FIG. 1 on a user's arm;

FIG. 3 is a Bottom plan view of the sleeve illustrated in FIG. 1 on a user's arm;

FIG. 4 is a Top plan view of the sleeve illustrated in FIG. 1 on a user's arm;

FIG. 5 is a Left side view of the sleeve illustrated in FIG. 1 on a user's arm;

FIG. 6 is a Right side elevation view of the sleeve illustrated in FIG. 1 on a user's arm;

FIG. 7 is a Bottom plan view of the sleeve illustrated in FIG. 1 laid out flat; and,

FIG. 8 is a Top plan view of the sleeve illustrated in FIG. 1 laid out flat.

The short dash-short dash-long dash type broken lines in the drawings illustrate environmental structure and form no part of the claimed design. The dash-dash broken lines in the drawings illustrate stitching that forms no part of the claimed design.

1 Claim, 4 Drawing Sheets
